Submerged Cook.
Samuel P. Reed.

The schedule reported in these Letters Patent, and making part of the same, containing a description in the words of the said Edward Reed, of his Improvement in manufacturing ovens from brick.

I construct a cistern of plank & timber about twenty feet long & eleven feet wide & five feet deep holding about two hundred barrels of water, with the corners rounded inside so as to form an oval or elliptical figure inside for the purpose of heating the water. I run a copper pipe commencing at one end where its diameter is about fifteen inches to receive the pipe & elsewhere about 6 inches & near a corner & hence close to the bottom the whole length of the cistern forming a right angle at each corner of the brick oval & back to the front end near the corner opposite to the one where it commences.

I put in a false bottom of boards over but near the pipe extending the whole length & width of the cistern for the purpose of keeping the water & pipe from coming in contact with the pipe with small holes therin for the passage of the water & heat on both sides of it.

I then construct a arch or arches in the middle of the bottom about three feet wide, & twelve feet long of an oval or elliptical form, having its exterior surface equal distant from the inside of the main cistern thereby forming a trough or channel for the rapid & easy circulation of the water & radish heat.

In this channel on one side of said arch, I place a paddle wheel about five feet in diameter, with four paddles as long as the channel is wide & extending nearly

bottom, which being connected with a water wheel is turned, so as to generate the whole body of water & punt in the channel a rapid motion by which the ~~bottom~~ or threads of the punt become entangled or separated more perfectly & in less time than by the process of boiling, simple as hereby provided, after which it is carefully dried & joined by machinery & becomes an article in texture & quality far superior to any that has been made in any other manner.

The bottom & parallel sides are covered tight to prevent the heat from escaping by evaporation.

The Drawing or Plan hereto annexed marked A represents the front end of the Machine or Bristle & the drawing or plan hereto annexed marked B represents the surface of the Machine including the centre & channel & wheel within the top or covering is removed.

The subscriber avers that he is the sole inventor of the principle & process aforesaid as well as of the mode of applying the same herein before described. That he claims as his invention & improvement and an article he purports his right to a Patent, is the method or principle of making bristles & preparing the punt for that purpose by keeping it in motion or circulation in hot water, whether the same be effected by the machinery & in the manner herein before described or by different machinery or in any other manner.

In testifying that the above is a true specification of my said Improvement as above described I have here set my hand at New Haven this 3rd day of May A.D. 1832.
